APPARATUS FOR SATURATING
ABSORBENT ARTICLESStuart P. Miller, Englewood, N. J., assignor to
The Barrett Company, New York, N. Y., a corporation of New Jersey

Application November 1, 1932, Serial No. 640,655

3 Claims. (Cl. 91—46)

This invention is directed to apparatus for saturating absorbent articles, and particularly, apparatus for continuously saturating and impregnating fibrous conduits employed to conduct and protect underground cables, telephone lines, electric light, and other conductors, and for the formation of water pipes and drain pipes to render them substantially waterproof and resistant to abrasion, corrosion, and conditions encountered above or underground by fibrous conduits. While, as above stated, the invention is particularly adapted for the saturation of fibrous conduits, it will be understood that it may be employed to saturate small fibrous or other articles requiring impregnation, such as spools, coils, etc., asbestos articles, concrete pipes, flashing blocks, etc. This application is a continuation in part of my copending application Serial No. 619,939, filed June 29, 1932.

The article to be saturated may, of course, be prepared in any known manner. In the case of fibrous bases for conduits, newsprint and paper pulp, or other fibrous material may be beaten in the usual paper beaters and the resultant stock screened and then pumped to paper cylinder machines and there formed into wet felts or paper. The wet paper may be wound about a cylindrical or other shaped tube or mandrel to produce a wet conduit of proper thickness. This conduit may be dried in kilns to remove the major portion of its moisture content. The fibrous base may, of course, be prepared in other known manner. Such conduits are made in several sizes, commonly varying from 2 inches to 6 inches or larger in internal diameter, have an average wall thickness of approximately $\frac{1}{8}$ of an inch and are usually produced in 5, 6, and 8 foot lengths. The wall thickness of the conduits may, of course, be greater or less than $\frac{1}{8}$ of an inch and other dimensions may vary. As they come from the drying kilns, they usually contain from 5 to 8 per cent moisture, although considerably more than 8 per cent moisture may, on occasion, be found present.

The porosity or absorptive characteristics of the walls of fibrous conduits may vary within wide limits from a very dense wall of density corresponding to hard wood and exceedingly difficult to saturate with low carbon water gas tar pitch or even with other waterproofing material, such as asphalt, to a porous open wall similar in density to that of roofing felt, which will readily absorb bituminous saturants. Samples of present commercial fibrous conduits have been tested and found to vary from substantially less than 1 cc.

of voids per gram of tube wall to 2.8 or more cc. of voids per gram of tube wall. To determine the cubic centimeters of voids per gram of tube wall, a small sample of tube wall (say 2" x 5") is dried for one hour at 100° C., cooled, desiccated and thereafter weighed. It is then immersed in kerosene, maintained at a temperature of 25° C., for 18 hours. Thereafter, the sample is removed from the kerosene, drained in vertical position for 30 seconds, and again weighed. The difference in weight represents the kerosene absorbed. This difference in weight in grams, divided by the specific gravity of the kerosene, corresponds to the cubic centimeters of kerosene absorbed. This volume in cubic centimeters, divided by the original weight in grams, gives the voids in cubic centimeters per gram.

It is an object of this invention to provide apparatus for saturating porous or absorbent articles in a simple and continuous manner. The apparatus of this invention is of high capacity low in operating and equipment costs, capable of automatic operation, materially reduces saturation costs, and results in uniformly saturated conduits of improved waterproofness and resistance to corrosion, abrasion, and soil pressures. Further, the apparatus is flexible and can readily be adapted to efficiently saturate articles varying widely in their porosity, e. g., dense or porous conduits, with different saturants.

As the saturant for the conduits, coal tar pitch, water gas tar pitch, asphalt, cutback pitches, blended pitches, or other waterproofing material may be used. A coal tar pitch having a melting point of from 140° to 180° F. is particularly suitable for saturation of fibrous conduits. Pitch of a melting point as high as 225° F. may be used in special cases, e. g., where conduits are to be exposed to temperatures which would soften the lower melting point pitches. Preferred pitches having melting points of from 140° to 180° F. or higher will have a "free carbon" content of from 5 to 9 per cent, but pitches of higher "free carbon" content up to from 15 to 25 per cent, or even higher may be used to give commercially satisfactory saturation under favorable conditions, e. g., in saturating articles having comparatively open wall structure.

Preferably, coal tar pitch made by a vacuum distillation process, such for example as disclosed in Patent No. 1,759,816, granted May 20, 1930, or other processes minimizing decomposition of the tar undergoing distillation, is employed as the saturant. Pitches made by a low temperature vacuum distillation process are characterized by

low "free carbon" content as compared with pitches made by higher temperature processes from the same tar, and I have found that such pitches are particularly suitable as the saturant for fibrous conduits.

Besides waterproofing absorbent articles such as conduits, this invention may be employed in fireproofing, oil proofing, gas proofing, insulating, painting and coloring such articles. For example, in fireproofing an article, it may be impregnated with an aqueous solution of inorganic salts, e. g., solutions comprising inorganic phosphates, in oil proofing a resin or cellulose solution may be used, in gas proofing and insulating the articles may be saturated with resin, cellulose or rubber mixture and in painting and coloring the articles may be impregnated with paints, lacquers, enamels or varnish.

This invention is particularly directed to apparatus for the saturation of conduits in plants having very large quantities of conduits requiring saturation. In accordance with the preferred embodiment of this invention, a tubular member of flattened U shape is disposed with the legs of the U immersed in saturant contained in tanks and thus sealed. The height of the legs is preferably made sufficient to accommodate a maximum barometric column of saturant with the upper portion of the U providing an evacuated space. Tracks are disposed in the saturating tanks running from one tank up through one leg of the tubular member, down through the other leg into the other tank, and returning to the first mentioned tank. The conduits may be placed in vertical position in cars which are arranged to run on the tracks. Thus conduits are carried by the cars through the saturant in one tank, up through the saturant in one leg of the tubular member, into the evacuated space in the upper portion of the tubular member, down through the saturant in the other leg of the tubular member, into and through the saturant in the other tank, and out from this tank. During the passage of the conduits from one tank to the other, out of contact with the saturant, draining and cooling thereof may take place.

In the preferred embodiment illustrated in the drawing, the invention is shown incorporated in the production of fibrous conduits saturated with bituminous material and the present disclosure will be confined to the present illustrated embodiment of the invention. It will be understood, however, that the novel features and improvements are susceptible to other applications, such, for example, to apparatus for saturating articles generally. Included in the scope of my invention is apparatus for saturation of conduits made of cement, concrete, cement-asbestos mixtures, or other porous or absorbent articles capable of being saturated. Hence, the scope of this invention is not confined to the specific embodiment herein described.

In the drawing, in which like reference numerals designate like parts,—

Fig. 1 is a vertical section, partly in elevation, of a preferred form of apparatus embodying this invention; Fig. 2 is a plan view of the apparatus shown in Fig. 1; and Fig. 3 is a vertical section, partly in elevation, of a modified form of apparatus embodying this invention.

Referring to Fig. 1; reference numbers 1 and 2 designate two large tanks spaced apart and each provided with a valve-controlled drawoff 3, an overflow pipe 4 near the top thereof and a pitch or other saturant pipe feed line 5. If desired

these tanks may be connected by means of a line (not shown) running from the base of one tank to the base of the other or one large tank 23 may be employed into which the ends of the tubular member hereinafter described extend, as shown in Fig. 3. Extending up from each tank is a tubular member composed of legs 6 and 7, each at an acute angle to the horizontal, this member preferably being of the shape shown in Fig. 1. The lower ends of legs 6 and 7 are open and dip beneath the saturant in tanks 1 and 2, the level of saturant therein being at all times maintained above the exit point from the legs 6 and 7, so that these legs are sealed by the liquid saturant within the tanks against the atmosphere. Tracks 11 on the base or floor plate 8 of the tubular member extend through the tanks, as indicated by the reference numeral 9 onto platforms 10 disposed contiguous to the tanks. Cars 12 are arranged to travel on the tracks 11. The tracks 10 extend from one tank 1 up through leg 6, down through leg 7, through tank 2, onto platform 10, and back to the tank 1. A series of cars 12, as shown in Figs. 1 and 2, are designed to travel onto the tracks being moved continuously or intermittently through the apparatus by a suitable cable or chain 13 passing between the tracks and over sheaves 14, 15 rotatably mounted adjacent tanks 1 and 2, respectively. Shaft 16, on which sheave 14 is keyed, has keyed thereon a pulley 17 over which passes a driving belt 18. This belt may be driven from any suitable source of power. A switch 22 is associated with the track 11 to permit the removal of cars from and the addition of cars to the series of cars running through the tanks 1, 2 and the tubular member.

The top of tubular member constituted of legs 6 and 7 is connected to a vacuum pump (not shown) by a line 19. Foam chambers and separators as disclosed in my copending application 40 may be disposed in line 19 to collect foam and return any volatile oils removed from the saturant. The tubular member is of such height, i. e., the point represented by reference numeral 20, extends above the level of saturant in tanks 1 and 2 to such height, that a maximum barometric column of saturant may be maintained in the legs 6 and 7. For coal tar pitch having a specific gravity of 1.2 this height should be in excess of 28 feet so that an evacuated space, indicated by 21, may be provided. If desired the height of the tubular member may be such that little or no evacuated space is provided above the level of saturant in the legs or such legs may be of a height insufficient to accommodate 55 a barometric column of saturant.

The cars may be loaded with the conduits in vertical position, as indicated in Fig. 1, just prior to their passage into tank 1, then caused to travel through tank 1, up through the column of saturant in leg 6 into the evacuated space 21, down through the column of saturant in leg 7 into the tank 2, and thence out of this tank, returning to tank 1. During the travel of the cars from tank 2 to 1 they may be passed first through heated 60 and then through cooled zones to expedite the draining and cooling of the conduits. Tank 1 may be elongated so that as the cars containing the conduits pass therethrough the conduits are immersed in saturant in tank 1 and soaked during 70 their passage through this extended path. In the case of wet conduits, partial or complete drying of the conduits may thus be accomplished.

The term "continuous" is used herein in a broad sense and is intended to include the passage of 75

conduits or other articles to be saturated intermittently, i. e., step-by-step through the drying and/or saturation zones, the articles remaining at rest for predetermined periods of time in their 5 passage therethrough, as well as the non-stop passage of the articles through the drying and/or saturation zones.

It will be noted that the apparatus of this invention is continuous, of high capacity, capable 10 of automatic regulation, requires a minimum of saturant for its operation and results in uniformly saturated conduits of improved waterproofness.

It is to be understood that this invention is not restricted to the present disclosure otherwise than 15 defined by the appended claims.

I claim:

1. In apparatus for saturating absorbent articles, in combination, a container for the saturant, a conduit composed of legs at an acute angle to 20 the horizontal, said legs extending above the saturant in the container and having open ends immersed in the saturant in the said container, means for maintaining vacuum conditions in said conduit, guide and supporting means mounted on 25 the interior surface of said legs, carriers for said articles disposed to travel on said guide and supporting means, and means for moving said carriers through said legs.
2. In apparatus for saturating absorbent articles, in combination, means for confining a saturant, a conduit composed of legs at an acute 30

angle to the horizontal, said legs extending above the saturant in the confining means and having open ends immersed in the saturant, means for maintaining vacuum conditions in said conduit, guide and supporting means mounted on the interior surface of said legs, carriers for said articles disposed to travel on said guide and supporting means, and means for moving said carriers through said legs. 5

3. In apparatus for saturating absorbent articles, in combination, two tanks for saturant at atmospheric pressure, a substantially U-shaped tubular conduit, the ends of the legs of the U constituting the inlet and outlet of said conduit, said inlet and outlet being, respectively, immersed 10 in the saturant in said tanks and thus liquid sealed against the atmosphere, means for creating a vacuum in the top of the said U-shaped tubular conduit, the legs of said U-shaped conduit being of a length more than sufficient to accommodate 15 a barometric column of saturant, thus providing an evacuated space in the upper portion of said U-shaped tubular conduit, rails passing through the saturant in one tank, through said tubular conduit, thence through the saturant in the other 20 tank and returning to the first mentioned tank forming a continuous circuit passing through said tanks and conduit, and cars for the absorbent articles arranged to travel on said rails. 25
